HASSOCK CONSTRUCTION

Harry Simon, Providence, R. I.

Application April 14, 1949, Serial No. 87,397

8 Claims. (Cl. 155—169)

1

The present invention relates to the manufacture of furniture, and has particular reference to a novel construction for a hassock.

The principal object of the invention is to provide a comfortable balanced hassock of very light weight.

A further object of the invention is to provide a light weight hassock of great strength, which will hold its shape during long usage.

Another object of the invention is to provide a simple assembly for a hassock which locks the parts together against accidental or inadvertent separation despite rough handling.

With the above and other objects and advantageous features in view, the invention consists of a novel arrangement of parts more fully disclosed in the detailed description following, in conjunction with the accompanying drawings, and more specifically defined in the claims appended thereto.

In the drawings,

Fig. 1 is a perspective view of a completed hassock constructed in accordance with the invention;

Fig. 2 is a top plan view of Fig. 1, the top being removed;

Fig. 3 is an enlarged section on the line 3—3 of Fig. 2;

Fig. 4 is a transverse vertical section through the hassock frame;

Fig. 5 is a bottom plan view of Fig. 1;

Fig. 6 is an enlarged perspective detail showing the locking of the spring member to the base member;

Fig. 7 is an enlarged sectional detail of the preferred staple engagement;

Fig. 8 is a section on the line 8—8 of Fig. 4; and

Fig. 9 is an exploded view showing the center supports of Fig. 8 in position for assembly.

It has been found desirable to provide a light weight hassock of great strength and durability, which will not be subject to distortion and which will not change in shape despite continuous use. To this end, I have made a hassock base of elements of extremely light weight, so joined and locked together that the base assembly is extremely strong; and I have mounted a spring member on the base and securely locked it to the base parts, the base and the spring member then being covered with flexible padding and encased in an ornamental cover.

Referring to the drawings, the hassock 10 is illustrated as of hexagonal shape, but the shape may obviously be round, square, or of other

2

geometric form as desired. A hassock base member is constructed by shaping an outer wall element 12 to the desired hassock shape, attaching a bottom 13 having an upturned rim 14 which is secured to the lower edge of the wall element, as by stapling, positioning a plurality of vertical panels 15, 16, and 17, of less height than the wall element 12 so as to interlock and to contact the wall element 12, and mounting a top 18 on the panels, the top being locked in place by a strip 19 which seats on the top edge and is stapled to the upper edge of the wall element.

The panels 15, 16, and 17, see Figs. 8 and 9, are of rectangular form, panels 15 and 17 having elongated vertical central slots 20 and 21 and panel 16 having spaced upper and lower central vertical slots 22, 23, whereby the panels interlock to form diametrical reinforcements for the base member 11.

A spring member 24 is provided, having a number of angularly disposed wire rods 25 which have central humps or loops 26 to rest together at their centers, and end humps or loops 27 adapted to receive a lock wire 28; a plurality of vertical springs 29 are mounted in spaced relation, as shown in Fig. 4, by interlocking the lower spring turns 30 with the lock wire 28 and the end loops 27. The upper turns of the springs are secured to a top wire 31 by means of metal clamps 32, see Fig. 2, the shape and size of the top wire corresponding to the shape and size of the upper edges of the annular wall element 12 and the strip 19. Small coil springs 33 are utilized to connect adjacent springs 29 together.

The wire rods 25 are preferably positioned to seat over the panels 15, 16 and 17 and are locked to the base member 11 by staples 34, see Fig. 7, which pass through the top 18 and over the sides of the panels. It is preferred to first interlock the panels, then place the top thereover, and then lock the spring member to the top and the panels; it is then feasible to pinch or distort the staple ends by a suitable tool to make a strong lock, the assembly then being seated within the wall element 12 and on the previously stapled bottom 13, whereby stapling the strip 19 to the upper edge of the wall element in place locks the parts together.

The material used for the base member may be thin plywood, but preferably is cardboard, as it has been found that the construction imparts great strength to corrugated cardboard and the like. To complete the hassock, the assembled

base member and spring member are covered with a layer 35 of resilient material such as hair or excelsior which is preferably encased in a protecting envelope of textile or paper, and with an outer layer 36 of a soft yielding material such as cotton wadding; an ornamental cover 37 of any suitable material, such as leather substitute, or textile material, is then drawn over the parts and locked in place by cementing the lower edges 38 to the bottom of the base member and cementing a protective sheet 39 of suitable material over the lower edges 38 and the remaining portion of the base member bottom.

It is thus clear that the improved hassock includes a spring member and a base member to which the spring member is locked, the base member being essentially a shell with interlocked reinforcing panels, whereby a honeycomb construction of very light weight results, the parts being extremely strong.

Although I have described a specific constructional embodiment of my invention, it is clear that changes in the size, shape, and materials of the parts, and in their locking relation, may be made to suit the requirements for different hassock designs, and that the invention may be applied to other articles of furniture, without departing from the spirit and the scope of the invention as defined in the appended claims.

I claim:

1. In an article of the type described, a light weight base including an outer wall, a bottom, vertical supporting panels positioned in said base and seated on the bottom, a top seated on the supporting panels, a spring assembly mounted on said base having spaced support rods, and lock elements securing the support rods to the top and the panels.

2. In an article of the type described, a light weight base including an outer wall, a bottom, vertical supporting panels positioned in said base and seated on the bottom, a top seated on the supporting panels, said panels being angularly spaced and interlocked, a spring assembly mounted on said base having spaced support rods, and lock elements securing the support rods to the top and the panels.

3. In an article of the type described, a light weight base including an outer wall, a bottom having an upright rim flange locked to the lower edge of the outer wall, vertical supporting panels positioned in the base and seated on the bottom, said panels being interlocked, a top seated on the supporting panels, said top being positioned below the upper edge of the outer wall, a spring assembly mounted on said base having spaced support rods, and lock elements securing the support rods to the top and the panels.

4. In an article of the type described, a light weight base including an outer wall, a bottom, vertical supporting panels positioned in said base and seated on the bottom, a top seated on the supporting panels, a spring assembly mounted on said base, said spring assembly including a plurality of spaced vertical spring elements having their lower ends secured to a lower lock ring and their upper ends secured to an upper lock ring, and radial support rods engaging the spring elements and the lower lock ring, and lock elements securing the radial support rods to the top and the panels.

5. In an article of the type described, a light weight base including an outer wall, a bottom, vertical supporting panels positioned in said base and seated on the bottom, a top seated on the

supporting panels, said panels being angularly spaced and interlocked, a spring assembly mounted on said base, said spring assembly including a plurality of spaced vertical spring elements having their lower ends secured to a lower lock ring and their upper ends secured to an upper lock ring, and radial support rods engaging the spring elements and the lower lock ring, and lock elements securing the radial support rods to the top and the panels.

6. In an article of the type described, a light weight base including an outer wall, a bottom having an upright rim flange locked to the lower edge of the outer wall, vertical supporting panels positioned in the base and seated on the bottom, said panels being interlocked, a top seated on the supporting panels, said top being positioned below the upper edge of the outer wall, a spring assembly mounted on said base, said spring assembly including a plurality of spaced vertical spring elements having their lower ends secured to a lower lock ring and their upper ends secured to an upper lock ring, and radial support rods engaging the spring elements and the lower lock ring, and lock elements securing the radial support rods to the top and the panels.

7. In an article of the type described, a light weight base including an outer wall, a bottom, vertical supporting panels positioned in said base and seated on the bottom, said panels being interlocked, a top seated on the supporting panels, said top being positioned below the upper edge of the outer wall, a spring assembly mounted on said base having spaced support rods, lock elements securing the support rods to the top and the panels, padding in the sides of said base and said spring assembly, and an ornamental cover over the padding.

8. In an article of the type described, a light weight base including an outer wall, a bottom having an upright rim flange locked to the lower edge of the outer wall, vertical supporting panels positioned in the base and seated on the supporting panels, said top being positioned below the upper edge of the outer wall, a spring assembly mounted on said base, said spring assembly including a plurality of spaced vertical spring elements having their lower ends secured to a lower lock ring and their upper ends secured to an upper lock ring, and radial support rods engaging the spring elements and the lower lock ring, lock elements securing the radial support rods to the top and the panels, padding in the sides of said base and said spring assembly, and an ornamental cover over the padding.

HARRY SIMON.
